UNITED STATES PATENT OFFICE.

GEORGE H. CLARK, OF BOSTON, MASSACHUSETTS.

DESIGN FOR A PROTECTING-STRIP FOR WHEEL-TIRES.

SPECIFICATION forming part of Design No. 28,381, dated March 15, 1898.

Application filed January 24, 1898. Serial No. 667,827. Term of patent 14 years.

To all whom it may concern:

Be it known that I, GEORGE H. CLARK, of Boston, county of Suffolk, and State of Massachusetts, have invented and produced a new 5 and original Design for a Protecting-Strip for Pneumatic Wheel-Tires, of which the following is a specification, reference being had to the accompanying drawings, forming a part thereof.

10 Figure 1 shows in side elevation my newly-designed protecting - strip for pneumatic wheel-tires, and Fig. 2 a cross-section of the strip shown in Fig. 1.

15 As shown in the drawings, the leading or characteristic feature of my design consists in a circular strip trapezoidal in cross-section.

The circular strip a has parallel sides or faces $a' a'$ and diagonal sides $a^2 a^2$.

I claim—

The design for a protecting-strip for pneumatic wheel-tires, as herein shown and described. 20

In testimony whereof I have signed my name to this specification in the presence of two subscribing witnesses.

GEO. H. CLARK.
